US00D794465S

(12) **United States Design Patent** (10) **Patent No.:** **US D794,465 S**
Wilkins et al. (45) **Date of Patent:** **** Aug. 15, 2017**

(54) **CONTAINER**

(71) Applicant: **The Procter & Gamble Company**,
Cincinnati, OH (US)

(72) Inventors: **Guy Baskerville Wilkins**, Cincinnati,
OH (US); **Brian Lee Floyd**, Cincinnati,
OH (US)

(73) Assignee: **The Procter & Gamble Company**,
Cincinnati, OH (US)

(**) Term: **15 Years**

(21) Appl. No.: **29/537,685**

(22) Filed: **Aug. 28, 2015**

(51) LOC (10) Cl. **09-01**

(52) U.S. Cl.

USPC **D9/529**; D9/723

(58) **Field of Classification Search**

USPC D9/516, 522, 528, 529, 541-543, 549,
D9/726; D28/4, 7; 215/381-385;
220/660, 669, 675
CPC A45D 34/041; A61H 23/02; A61H
2015/0064; A61H 2201/0107; A61H
2201/105

(57) **CLAIM**

The ornamental design for a container, as shown and
described.

DESCRIPTION

FIG. 1 is an isometric view of a container, showing our new
design;

FIG. 2 is a front view thereof;

FIG. 3 is a right view thereof;

FIG. 4 is a back view thereof;

FIG. 5 is a left view thereof;

FIG. 6 is a top plan view thereof; and,

FIG. 7 is a bottom plan view.

1 Claim, 3 Drawing Sheets
